UNITED STATES PATENT OFFICE.

NELSON D. HOSLEY, OF MERIDEN, CONNECTICUT, ASSIGNOR TO THE WILCOX & WHITE COMPANY, OF MERIDEN, CONNECTICUT, A CORPORATION OF CONNECTICUT.

HORIZONTAL-GRAND PLAYER-PIANO.

957,421.

Specification of Letters Patent.

Patented May 10, 1910.

Application filed April 28, 1909. Serial No. 492,644.

To all whom it may concern:

Be it known that I, NELSON D. HOSLEY, a citizen of the United States, residing at Meriden, county of New Haven, Connecticut, have invented certain new and useful Improvements in Horizontal-Grand Player-Pianos, of which the following is a full, clear, and exact description.

My invention relates to improvements in mechanical music playing instruments and particularly to so-called "player pianos," the invention being especially adapted and constructed for pianos of the horizontal grand type.

15 My invention aims at simplifying and improving many features of mechanical construction.

Because of the design of a horizontal grand piano, it has heretofore been found practically impossible to embody playing apparatus therewith without seriously affecting said design inasmuch as it has required the presence of unsightly extensions, which not only materially disturb the conventional design of such instruments but also makes packing and transportation expensive and difficult. My invention not only overcomes these defects but provides a construction whereby the player mechanism 25 may be very readily applied or removed for the purposes of repair or adjustment at any time. These and other advantages will appear from a reading of the following specification and an examination of the accompanying drawings.

In the drawings, Figure 1 is a plan view of a horizontal grand piano, partly broken away. Fig. 2 is a front elevation of a horizontal grand piano, partly broken away. 40 Fig. 3 is a side elevation of said instrument partly broken away. Fig. 4 is a relatively enlarged view mainly in section and showing the location of my action and the method of mounting the same.

45 1 represents the case of a horizontal grand piano having an elongated front portion by which I mean wider at the front than at the rear end and having a horizontally disposed sounding board therein.

50 1^a—1^a are the legs supporting the case.

2 represents the so-called lyre which carries the usual piano pedals, and which is also provided with pumping pedals, one of which is indicated at 3. As shown, the

pumping pedal 3 is mounted upon a hinged 55 support 4 carried by the lyre 2, whereby said pedal 3 may be folded back into a small box-like space or housing at the foot of the lyre.

5 is an exhauster bellows arranged within 60 the case of the piano and well to the rear of the same and underneath the sounding board. The pumping pedal 3 is connected by suitable levers and links 8—9—10—11—12 with the exhauster 5.

65 14 represents the front panel, which is arranged directly to the rear of the keyboard 15.

16 represents one of the hammers by which the strings 6 are struck.

70 17 represents the frame of the mechanical action.

The action pneumatic mechanism may be of any suitable type and hence it need not be explained in detail herein. It should however be stated that the frame of the action is so constructed that said action, tracker mechanism, and motor are entirely contained and carried thereby, whereby, when said frame is removed, all of said parts will be 75 80 bodily removed.

18 represents the tracker carried by the action frame, the same being located directly to the rear of a window or opening in the front panel 14, and forward of the primary 85 and power pneumatics. 29 represents the primary, and 30 the power, pneumatics. 14^a represents a suitable closure for said opening when said mechanical action is not to be employed.

90 19 conventionally represents a note sheet traversing the tracker 18 and mounted upon suitable spools 19^a carried by the usual spool frame, the details of which are not necessary to describe or illustrate, it being merely necessary to understand that the support for the spools is a unitary part of the action casing, whereby, when the casing is removed, the tracker, spools, spool frame, etc., will be removed therewith. The motor conventionally 95 shown at 20 for driving the spools 19^a 19^b is also carried by the action frame 17 at one end thereof and in substantially the same horizontal plane.

100 21 represents the duct leading from the exhauster 5 to the pneumatic action mechanism, the same being suitably connected with one wall of said action frame, whereby, when

the latter is in place, said duct will be properly connected therewith. In the form shown, the exhauster duct 21 makes connection with the rear wall of the action frame, as shown in Fig. 4, and said action frame is held thereto by suitable screw bolts 22 at the ends of said action frame, the forward ends of which may be provided with suitable handles 22^a which are easy of access from the front of the piano after the front panel is removed to enable the entire pneumatic action to be disconnected for removal or connected for use. It will be observed that all the constituent parts of the action are carried as a unitary structure.

It is preferable to provide a hinged cover 23, which may be connected by a hinge 24 to the action frame, said cover being located under the music desk 25, which in turn is located under the cover 26 of the case 1. The function of the cover 23 is to protect the tracker and yet being hinged, the same may be swung back at any time for the purpose of facilitating the insertion of note sheet rolls. In removing the action, it would be preferable to first remove the cover 23 although this is not essential.

By the above arrangement of parts, it will be seen that all the mechanism is conveniently housed without involving any unsightly projections from the conventional piano case. The particular location of the action is such as to afford very marked advantages. All of the parts are of easy access, particularly the action and associated parts. The exhauster bellows can readily be removed from the under side of the case. The only respect in which the apparatus is seen to differ from the ordinary grand piano is in the provision of a lyre suitable for housing the mechanism of the pumping pedals with the linkage leading therefrom to the exhauster. As already suggested, I need not at length describe the action mechanism, since it may include any suitable construction by which notes may be mechanically struck so long as the said construction is susceptible of the arrangement shown herein by which the advantages set forth are attained.

27 represents one of the strikers carried by a part of the action frame 17, the striking end of said striker 27 being arranged in close proximity to that end of the key which is manually engaged when the instrument is played by hand, by which arrangement this striker strikes down upon the key, and by reason of its location relatively to the key, produces, as I have found, results more nearly approximating manual playing than where the striker engages the key nearer the balance rail, or to the rear of the balance rail and under the key. These and other advantages which will be appreciated by the mechanic skilled in this art, all cooperate to 65 the securing of superior musical effect, as

well as providing a means which possesses many mechanical advantages already defined.

It will be seen that my invention may be applied to any ordinary grand piano case, without requiring any abnormal increasing of its thickness vertically, or without requiring any box-like extension of the case on its lower side. If the front panel is too close to the forward edge of the plate 31, or the sounding board 32, to afford room for the action and tracker mechanism, all that is required is to somewhat enlarge said space, as by employing a somewhat shorter plate and sounding board.

What I claim is:

1. In a horizontal grand piano, a horizontal case, sounding devices therein, hammers therefor, pivoted keys and mechanical devices for operating said hammers, said mechanical devices including key strikers and pneumatic action mechanism arranged entirely within the front part of the case directly to the rear of the outer ends of the keys, and arranged to operate said hammers from a point forward of the pivots for said keys, and tracker mechanism above said strikers and in front of said action mechanism.

2. In a combined mechanically and manually operable grand piano, a frame having an elongated front portion, a horizontally disposed sounding board in said frame, and a tracker-board and pneumatic action mechanism mounted entirely within the elongated front portions of the case, said tracker mechanism being arranged forward of said action mechanism and in substantially the same horizontal plane.

3. In a combined mechanically and manually operable grand piano, a frame having an elongated front portion, a horizontally disposed sounding board therein, sounding devices therein, keys therefor having exposed outer ends along the elongated front portion, combined pneumatic action mechanism, tracker board and music roll carrying mechanism mounted entirely within the elongated front portion of the frame, said parts being removable bodily through the said front portion, said tracker board and music roll carrying mechanism being arranged in substantially the same horizontal plane as, and in front of, said action mechanism.

4. In a combined mechanically and manually operable grand piano, a frame having an elongated front portion, a horizontally disposed sounding board therein, sounding devices therein, keys therefor having exposed outer ends along the elongated front portion, combined pneumatic action mechanism, tracker-board, music roll carrying mechanism and motor therefor mounted entirely within the elongated front portion of

the frame, said parts being arranged in substantially the same horizontal plane, the tracker mechanism being in front of said action, and said motor being at one end of 5 said tracker.

5. In a combined pneumatic and manually operable grand piano, a frame having an elongated front portion, a horizontally disposed sounding board in said frame, 10 mechanical player mechanism in front of said sounding board including pneumatic action mechanism, a tracker, spool mechanism, and motor mechanism therefor, all of said parts being in substantially the same 15 horizontal plane, and a frame dependently supporting and carrying all of said mechanical player parts all arranged entirely within the elongated front portion of the piano frame, with means at the ends of said frame 20 for detachably holding said frame in place.

6. In a combined pneumatic and manually operable grand piano, a frame having an elongated front portion, a horizontally disposed sounding board in said frame, 25 mechanical player mechanism including pneumatic action mechanism, a tracker, spool mechanism, and motor mechanism therefor, a frame dependently supporting and carrying all of said player parts all ar- 30 ranged entirely within the elongated front

portion of the piano frame, with means for detachably holding said frame in place, an exhauster in said piano case under the sounding board and to the rear of said pneumatic action mechanism, and a duct carried by the 35 piano frame, said duct leading from said exhauster to the removable action carrying frame.

7. In a combined pneumatic and manually operable grand piano, a frame having an elongated front portion, a horizontally disposed sounding board in said frame, a keyboard at the elongated front end of said piano frame, a front panel at the rear of said keyboard, the keys of said keyboard extending under and to the rear of said front panel, assembled pneumatic action mechanism including strikers arranged above said keys and directly to the rear of the front panel, said strikers being arranged to engage the upper sides of said keys immediately to the rear of said panel, said pneumatic action mechanism also including power pneumatics and a tracker above the plane of the strikers but in substantially the 55 same horizontal plane.

NELSON D. HOSLEY.
